UNITED STATES PATENT OFFICE.

JOSEPH B. FISCHER, OF HAMILTON, ASSIGNOR OF TWO-THIRDS TO MARTIN BARE, OF CINCINNATI, OHIO.

ICE MARKER AND PLOW.

SPECIFICATION forming part of Letters Patent No. 258,637, dated May 30, 1882.

Application filed February 6, 1882. (No model.)

To all whom it may concern:

Be it known that I, JOSEPH B. FISCHER, of Hamilton, Butler county, Ohio, have invented certain new and useful Improvements in Ice 5 Markers and Plows, of which the following is a specification.

My invention relates to that class of ice-markers which are used to mark out a field of ice previous to running over it with the ice-plow, and has special reference to the guide by which the marker is made to follow a previously-marked line.

Referring to the drawings forming part of this specification, Figure 1 is a side elevation 15 of a marker constructed after the principles of my invention. Fig. 2 is a top view of the same. Fig. 3 is an enlarged view of the forward end of the beam. Fig. 4 is an enlarged view of the rear end of the beam and a portion of the handles. Fig. 5 is a view of the rear end of the marker, looking toward the front.

The beam A is formed in the usual manner, having the various teeth a attached thereto. 25 The lower ends of the handles A' are attached to the beam A by the angle-plates a', and are braced in a manner to be hereinafter described.

The guides heretofore employed on ice-markers have been in form of a plate extending 30 nearly the entire length of the beam, and attached at each end to the beam by a rod, which is hinged to the beam to permit the guide to be turned from one side of the marker to the other. This form of guide is objectionable for 35 the reason that it is unnecessarily heavy, and is apt to bind in the groove in the ice in which it travels, and thus it soon gets loose and out of order. To remedy this defect I employ the short guide-plate B, located at the forward 40 end of the beam. This short guide-plate is attached to the arm B', which in turn is attached to the rod or shaft C, journaled on top of the beam. It is sometimes desirable to cut the blocks of ice larger than at other times, 45 and heretofore in order to do this it has been necessary to use a separate marker for each different size of block; but I construct my marker so that I am enabled to mark different widths of blocks by making the arm B' in two

sections, 1 and 2, the section 1, to which the 50 guide-plate B is attached, being capable of sliding on the section 2 and of being secured in the desired position by a bolt, 3, or its equivalent, by which means the guide-plate may be set at different distances from the beam. A rod, b, 55 extends from near the end of the arm B' to the shaft C, to properly brace the guide arm and plate. At the forward end of the beam is the end or clevis block D, which is bolted to the beam, and to which the clevis D' is connected. This end block is provided with a bearing, d, in which the forward end of the shaft C is journaled. The rear end of the shaft C is journaled in the cross-bar e, which 60 unites the ends of the semicircular plate E, 65 and this plate and the cross-bar e are secured to the beam A by the flanges e', which are bolted to the beam.

Bolted to the plate E are angle-irons or braces E', to which the handles A' are also 70 bolted, bracing them securely in position, thereby dispensing with the rods which ordinarily extend from the handles to the beam.

At or near the center of the shaft C, I place a journal-box, d', the shaft at this point being 75 round to turn freely in the journal-box.

To the rear end of the shaft C is attached the crank F, by which the shaft C may be turned. The purpose of this turning of the shaft is to 80 reverse the guide-plate B from one side of the beam to the other, as is necessary to mark back and forth across the field.

To hold the guide-plate down firmly on the ice, the crank F is provided with a spring-pawl, G, one end of which is capable of entering notches h in the semicircular plate E. When the guide-plate is on the ice on one side of the beam the end of the pawl G is in the notch h on the same side, and when it is desired to reverse the guide-plate to the other 90 side of the beam the end g of the pawl is pressed down on the crank-handle, thus removing the opposite end of the pawl from the notch, and the crank is turned over to the other side, and the plate is thus reversed. If 95 it is desired to hold the guide-plate entirely from the ice, the end of the pawl is allowed to enter the notch in the top of the semicircular

plate, when the guide-plate will be held above the beam.

While the spring-pawl G and the notches *h* are the devices which I prefer to employ for retaining the guide-plate in the desired position, I do not confine myself to this special form of device, as other devices may be employed to accomplish the same purpose.

From the above description it will be seen that my improved marker is light and convenient and yet firm.

The ice marker and plow are sometimes combined in one, in which case the guide-plate and its connections, as above described, are equally advantageous.

What I claim as new and of my invention, and desire to secure by Letters Patent, is—

1. The beam A, having a shaft, C, journaled to its upper edge, and extending from the front 20 to the rear end of said beam, in combination with the guide-plate B, attached to the shaft C by the adjustable arm B', the rear end of said shaft being provided with means for turning the guide-plate from one side of the beam 25 to the other, substantially as and for the purposes specified.

2. The combination of the shaft C and the guide-plate B, connected to said shaft by the arm B', said arm being constructed in two sections, 1 and 2, one section being capable of sliding on and being secured at the desired point to the other section, substantially as and for the purposes specified.

3. The combination of the beam A and the shaft C, extending from the front to the rear end of said beam, the front end of said shaft being provided with a guide-plate, B, and the rear end with mechanism for rotating said shaft to carry the guide-plate from one side of the 35 beam to the other, substantially as described.

4. The beam A, provided at its front end with the clevis-block D and at the rear end

with the bearing-plate e, in combination with the shaft C, provided with the guide-plate B, one end of said shaft being journaled in the 45 clevis-block and the other end in the bearing-plate e, said shaft being provided with means for causing it to rotate, substantially as and for the purposes specified.

5. The combination of the beam A and the shaft C, the latter provided with a guide-plate, B, and mechanism for rotating said shaft to carry the guide-plate from one side of the beam to the other, and for holding the shaft and guide-plate in the desired positions, substantially as and for the purposes specified.

6. The beam A, provided with plate e and semicircular plate E, in combination with the shaft C, provided with the crank F, said crank and semicircular plate being provided with 60 means for causing the crank to be held in the desired position, substantially as and for the purposes specified.

7. The beam A, provided with the clevis-block D and the semicircular plate E, said 65 plate being provided with notches *h*, in combination with the shaft C, provided with the crank F and spring-pawl G, substantially as and for the purposes specified.

8. The beam A, constructed substantially 70 as described, in combination with the shaft C, journaled at each end of the beam and at or near the center in the clip or box d', substantially as and for the purposes specified.

9. The beam A, provided with the semicircular plate E, in combination with the handles A', secured to the beam by the plates a' and to the semicircular plate by the angle-irons or braces E', substantially as and for the purposes specified.

JOSEPH B. FISCHER.
